ELECTRODE STRUCTURE

Jacob Kurtz, Teaneck, N. J., assignor to Eisler Electric Corporation, Union City, N. J., a corporation of Delaware

Application November 9, 1939, Serial No. 303,561

4 Claims. (Cl. 176—126)

This invention relates to new and useful improvements in electrode structures for electrical discharge devices.

The object of the invention is an electrode assembly which may be mounted in an envelope without any special centering or spacing devices other than wires serving as leading-in conductors.

With this object in view, three embodiments will be described for the purpose of exemplifying the invention.

In the drawing

Fig. 1 is a side elevation of a discharge tube of a conventional type in which the electrode structures of the present invention may be mounted;

15 and

Figs. 2, 3 and 4 are perspective views of three embodiments of the present invention.

Referring to Fig. 1, 1 is a glass envelope enclosing electrodes 2 and 2'. The electrodes are metal cylinders closed at the bottom where lead-in wires such as 3 and 4 are welded thereto. Wires 3 and 4 are either of the same kind of metal as the electrodes or of one which may be readily welded thereto and are sealable into the wall of the glass envelope as indicated at 5. The bottom of the electrode should be as close as possible to the "press" 5. By virtue of the construction to be presently described, the conductors 3 and 4 serve not only as lead-in wires but also as the sole supports for the electrode and the sole means for properly positioning it, e. g., with respect to the envelope 1.

As shown in Fig. 2, the lead-in conductors 3 and 4 are constituted by a single wire bent into a U the connecting portion of which is flattened as shown at 6. The closed bottom of the electrode is welded to the flattened portion at two points 7. This will insure a firm support for the electrode in axial alignment with the legs 3 and 4 of the U. When legs 3 and 4 are sealed at 5 into the envelope, the electrode 2 will be centered within the glass tube 1 and it will not be necessary to provide special centering means or protectors to prevent contact between the electrode and the glass envelope. This is insured by the securing of the electrode to a flat instead of a rounded surface and by the provision of a plurality of leading-in wires for each electrode.

50 Current supply may be effected through either leg 3 or 4.

The embodiment shown in Fig. 3 is like the one in Fig. 2. However, in order to insure the stability of the electrode assembly against distortion transversely to the plane in which the leading-in wires lie, corrugations 8 and 9 are

formed in legs 8 and 9 of the U. These corrugations point in opposite directions at right angles to the plane through 8 and 9.

In the structure shown in Fig. 4 the arrangement of Fig. 3 is substantially duplicated at 14, 15, 16, 17, corresponding to 8, 9, 10, 11. However, legs 14 and 15 are connected with leading-in wires 12, 13. Legs 14 and 15 or 12 and 13, or both, may be sealed in the walls of the glass envelope. This arrangement is particularly useful in lamps requiring copper-clad leading-in wire or the like which is not rigid enough to serve as the sole electrode support or which can not be readily welded to the electrode. 12 and 13 are such leading-in wires. Through two or three steps 18 and 19, these leading-in wires may be secured to nickel, nickel alloy or the like wires 14, 15 which possess the necessary characteristics for acting as the sole electrode support.

What is claimed is:

1. In an electrode structure for electric discharge device having an envelope, a metal cylinder, a U shaped wire the connecting piece of which is secured to the cylinder and the two legs of which pass through and are sealed into the wall of the envelope, and a corrugation formed in each leg between the seal and the connecting piece pointing in opposite directions at right angles to a plane passing through the legs.

2. In an electrode structure for electric discharge device having an envelope, a metal cylinder, a U shaped wire the connecting piece of which is flattened and fastened to the cylinder and the two legs of which pass through and are sealed into the wall of the envelope, and a corrugation formed in each leg between the seal and the connecting piece pointing in opposite directions at right angles to a plane passing through the legs.

3. In an electrode structure for electric discharge device having a glass tube envelope, a metal cylinder closed at one and open at the opposite end, a support for said cylinder consisting solely of a U shaped wire of a metal that may be readily welded thereto, the connecting piece of the U being flattened and welded at a plurality of points to the closed end of the cylinder, the two legs of the U passing through and sealed into the wall of the glass tube, and a corrugation formed in each leg between the seal and the connecting piece pointing in opposite directions at right angles to a plane passing through the legs.

4. In an electrode structure for an electric discharge device having a glass tube envelope, a metal cylinder closed at one and open at the

opposite end, a support for said cylinder consisting solely of a U shaped wire of a metal that may be readily welded thereto, the connecting piece of the U being flattened and welded at a plurality of points to the closed end of the cylinder, and the two legs of the U passing through and sealed into the wall of the glass tube, a corrugation

formed in each leg between the seal and the connecting piece pointing in opposite directions at right angles to a plane passing through the legs, leading-in wires of a different material, and multi-step welds connecting the legs of the U with the leading-in wires. 5
